UNITED STATES PATENT OFFICE.

CLIFFORD A. FLEMING, BURTON S. FLEMING, AND CHARLES F. LADWIG, OF HUNTSVILLE, MISSOURI.

BALING-PRESS.

1,215,014.

Specification of Letters Patent. Patented Feb. 6, 1917.

Application filed February 15, 1915. Serial No. 3,420.

To all whom it may concern:

Be it known that we, CLIFFORD A. FLEMING, BURTON S. FLEMING, and CHARLES F. LADWIG, citizens of the United States, residing at Huntsville, in the county of Randolph and State of Missouri, have invented certain new and useful Improvements in Baling-Presses; and I do declare the following to be a full, clear, and exact description 10 of the invention, such as will enable others skilled in the art to which it appertains to make and use the same.

Our invention relates broadly to improvements in baling presses, and more particularly to the means for feeding the unbaled material into the baling chamber.

Heretofore, for this purpose, a rigid plunger has been provided, together with means for forcing said plunger inwardly into the 20 baling chamber in order to force a quantity of material, in advance of said plunger, into said chamber. It has been found, however, that in case too much of such material is disposed in advance of the plunger, as often 25 occurs, the same is either wedged very tightly within the inlet end of the baling chamber, or is entirely prevented from entering such chamber. This is very undesirable since it not only causes unnecessary 30 friction and therefore requires greater power to operate the press, but because of the fact that certain parts of the machine are often broken by the sudden stoppage of the plunger.

It is to overcome this most undesirable 35 feature of the present day baling press, that we have devised our invention which is to be hereinafter fully described and claimed and which is shown in the accompanying 40 drawings wherein:—

Figure 1 is a vertical longitudinal section through the receiving chamber and a portion of the baling chamber of a baling press, showing a contractible plunger with which 45 the machine is provided, in side elevation and in its normal condition;

Fig. 2 is a view similar to Fig. 1 but showing the plunger in longitudinal section, this view likewise illustrating the condition of 50 the plunger when an overload of material is being projected thereby, the aforesaid

figures likewise disclosing respectively, the normal and operative positions of a gate member with which the inlet of the baling press is equipped;

55

Fig. 3 is a horizontal section as seen along the plane indicated by the line 3—3 of Fig. 2;

Fig. 4 is a vertical transverse section taken along the plane of the line 4—4 of Fig. 1. 60

In these drawings, constituting a part of the application, C designates the receiving chamber of a baling press which is provided with any preferred type of hopper H at its upper end, into which the material to be 65 baled is fed and rammed by the usual vertically moving head (not shown). Communicating by a throat T, with one side of the receiving chamber C, is a baling chamber B—C which may be of any preferred 70 type and which is here shown as extending horizontally from said one side of the chamber C, while extending from the opposite side thereof, is a plurality of tracks or rails R upon which guide rollers with which 75 the plunger P is equipped, are adapted to travel.

As this plunger is reciprocated by any preferred means, not shown, and as it forces the unbaled hay or straw into the baling 80 chamber, it becomes expedient to provide means whereby, should an excessive amount of such material be positioned in advance of the plunger P and thereby forced toward the baling chamber, such an excessive amount 85 will be prevented from wedging between the upper side of the plunger and the upper side of the throat T. For accomplishing this result, we provide means whereby said throat T may expand, under such circumstances, and likewise so construct the plunger as to allow it to contract. 90

In the present embodiment, the upper side of the throat T is shown as equipped with a horizontally extending transverse gate member or bar 1 whose upper edge is pivotally supported at 2 and equipped with an upstanding ear 3 to which one end of a coil spring 4 is connected, said spring extending toward the baling chamber and being secured to the upper wall thereof, whereby to 100 exert its tension to normally retain the gate

member 1 in upright position, in which position, its lower edge constitutes the upper side of the throat T as will be evident by an inspection of Fig. 1 of the drawings. It will be evident however, that this gate member can yield inwardly into the baling chamber to the position seen in Fig. 2, thereby allowing the size of the neck to be increased and more readily allowing the charge of un-baled material to be forced into said chamber. This is one means of preventing wedging of the plunger within the throat T, under abnormal circumstances, but it is preferably employed in connection with a 15 tractible plunger such for instance as that shown in the drawings.

This plunger comprises a pair of upright cheek or side plates 5 whose forward lower corners are provided with depending extensions 6 to which rollers 7 are revolvably connected, these rollers traveling upon the bottom of the chambers C and B—C. On the other hand, the rear ends of the plates 5 are provided with rollers 8 which 20 travel upon guide rails R, previously described and with a pair of upstanding ears 9 to which a substantially horizontal deck 10 is pivoted at its rear end, said deck constituting the upper side of the plunger and 25 having its forward end extended downwardly as seen at 11 to form an apron in advance of the upright end plate 12 which connects the front edges of the plates 5. Completing the construction of the plunger, is a 30 coil spring 13 which is disposed between the deck 10 and a stop flange 14 which projects rearwardly from the plate 12, and an upright bolt 15 which depends from said deck through the spring and through the flange 35 14 and whose lower end is provided with a stop 16 for limiting the upward movement of the deck 10. In the present case, a pair of links L are shown as pivoted to the axle upon which the rollers 8 are mounted, these 40 links being reciprocated by any preferred means.

By constructing the plunger P in the manner just described, it will be seen that the deck 10 may yield downwardly under 45 the undesirable conditions before set forth, thus preventing the plunger from being checked in its forward movement, preventing it from wedging in the baling chamber, and allowing lighter power to be provided 50 for operating the machine. Although this plunger P is preferably employed in connection with the gate member 1 previously described, it will be evident that it could well be employed were such gate member dis- 55 pensed with.

From the foregoing description, taken in connection with the accompanying drawings, it will be evident that very simple means have been provided for accomplishing the object of the invention, yet that a 60

machine constructed in the manner described and illustrated, will be very efficient in operation and will possess a number of advantageous features.

I claim:

1. A baling press comprising a receiving chamber having in its top an inlet, a baling chamber extending horizontally from said receiving chamber, a pair of horizontal tracks extending across the bottom of the receiving chamber and into the baling chamber, an additional pair of horizontal tracks spaced above said first-named tracks and also extending across the receiving chamber into the baling chamber, a transverse shaft 70 having rollers at its ends mounted on said last-named tracks, a reciprocating bar leading rearwardly from and connected with said shaft, a pair of side members extending forwardly from and connected to the 75 ends of said shaft, said members having rollers at their front end traveling on the first-named tracks, a transverse upright plate extending between and secured to said front ends of said members, a flat substantially horizontal compressible deck overlying said members, an upright apron depending from the front end of said deck in substantially parallel relation to the aforesaid plate, a hinge connecting the rear end of 80 said deck to the rear end of the aforesaid members to receive all rearward thrust exerted on said deck, and a spring beneath the latter for yieldingly upholding the same. 85

2. A baling press comprising a receiving chamber having in its top an inlet, a baling chamber extending horizontally from said receiving chamber, a pair of horizontal tracks extending across the bottom of the receiving chamber and into the baling chamber, an additional pair of horizontal tracks spaced above said first-named tracks and also extending across the receiving chamber into the baling chamber, a transverse shaft 90 having rollers at its ends mounted on said last-named tracks, a reciprocating bar leading rearwardly from and connected with said shaft, a pair of upright parallel side plates connected with and extending forwardly from said shaft, an upright transverse front plate 95 secured to and connecting the front ends of said side plates, rollers at the lower front corners of said side plates traveling on the first-named tracks, a substantially horizontal deck overlying said side plates and said front plate, said deck having its front end bent downwardly into sliding engagement with the front face of said front plate, a stop rigidly secured to and projecting rearwardly from the aforesaid front plate, said 100 stop having an aperture therethrough, an upright rod connected to and depending from said deck through said aperture, a coiled spring surrounding said rod between the deck and stop to yieldingly uphold the 105

former, an additional stop on the lower end of said rod for coöperation with the other stop to limit the upward movement of said deck, and hinge means connecting the rear end of 5 said deck with the rear upper corners of the aforesaid side plates to receive all rearward thrust exerted on said deck.

In testimony whereof we have hereunto

set our hands in presence of two subscribing witnesses.
